(57) **CLAIM**

The ornamental design for a vehicle instrument cluster, as shown and described herein.

DESCRIPTION

FIG. 1 is a perspective view of a vehicle instrument cluster showing a new design.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof; and,

FIG. 8 is a perspective view of the vehicle instrument cluster installed behind a steering wheel.

The broken lines in FIG. 8 are used to illustrate environmental features that form no part of the claimed design.

1 Claim, 8 Drawing Sheets
